CLAIM

The ornamental design for a vibrating teething ring, as shown and described.

DESCRIPTION

FIG. 1 is a perspective view of a vibrating teething ring, showing my new design;

FIG. 2 is a top plan view thereof, the bottom plan view being a mirror image of the top plan view; and,

FIG. 3 is a front elevational view of the vibrating teething ring, the rear, left side, and right side elevational views being mirror images of the front elevational view.
